UNITED STATES PATENT OFFICE.

WALTER MCGEE AND DAVID MCGEE, OF PAISLEY, SCOTLAND.

MACHINE FOR BALLING YARN.

SPECIFICATION forming part of Letters Patent No. 654,351, dated July 24, 1900.

Application filed February 14, 1900. Serial No. 5,153. (No model.)

To all whom it may concern:

Be it known that we, WALTER MCGEE and DAVID MCGEE, citizens of the United Kingdom of Great Britain and Ireland, residing at 5 Stoneybrae, Paisley, county of Renfrew, Scotland, have invented certain new and useful Improvements in Machines for Balling Yarn or Thread, (for which application for patent has been made in England, No. 14,936, dated 10 July 20, 1899,) of which the following is a specification.

This invention relates to machines for winding yarn or thread into balls; and it has for its object to provide, in conjunction with the 15 thread-cutting mechanism of such balling-machines, mechanical appliances for drawing the cut end of the thread within the convolutions of the ball before the latter is removed from the winding-spindle, whereby the time, 20 labor, and expense involved in so fixing the thread end by hand are avoided.

The invention is illustrated by the accompanying drawings.

Figure 1 is a view of the frame of a machine 25 for balling yarn or thread, showing the improvements applied thereto. Figs. 2 and 3 are plans, to a larger scale, of the mechanical appliance in two different positions; and Fig. 4 is an elevation of Fig. 2, taken in the direction of the arrow, Fig. 2. Fig. 5 is a modification of a detail hereinafter referred to.

In carrying out the invention we secure upon the bracket-support A of the thread-cutter B, provided for each ball-spindle, a 35 guide A', wherein is fitted to slide crosswise a rod or bar D, carrying adjustably thereon a needle E, provided with an eye E' and bent or directed toward the cutter B. The needle-supporting arm is secured on rod D by means 40 of the clamping bolt and nut D'. By loosening the latter the needle may be adjusted on rod D. The adjustment may be otherwise effected. The bar D, with the needle, is reciprocated or pressed inward by a wedge or 45 cam-piece F, carried by the sliding cutter-bar B, which is actuated in the usual way from a hand-lever, and upon the sliding cutter B is secured a hook or crochet-needle G, which as it moves forward with the cutter-bar B is arranged to enter the eye of the needle E. Cam-piece F has a slot composed of a part J, perpendicular to bar D, and a part K, inclined

thereto. L is a rod projecting from standard M, which is clamped to rod D into the cam-slot. The shape of the slot is such that during the first part of the downward movement of the cutter B (from the position shown in Fig. 2) rod L is in the part J of the slot and rod D is not moved. During the movement just described the yarn is cut, and hook G is 60 pulled from eye E'. Then as the inclined part K of the slot operates on rod L needle-bar D is moved backward thereby.

In the operation of the device when the thread ball X has been wound the cutter is 65 actuated by a cam H on a shaft N, provided with a hand-wheel O, as shown at Fig. 1, to bring the cutter mechanism into position to cut the thread, and by the movement of the cam-piece F thereby effected the needle E is 70 pressed through the outer convolutions of the ball-thread, as shown at Fig. 2, the crochet-hook G at the same operation passing through the needle-eye. The flier of the balling-machine then moves to lay the thread across the 75 hook G, which on being drawn back on the return movement of the cutter mechanism engages the thread as it is cut and draws the cut end through the eye of the needle E. The movements of the needle E and hook G being 80 suitably timed, the needle E is then retracted clear of the ball X to the position shown at Fig. 3, drawing the cut end of the thread with it through the outer thread convolutions and leaving it in the ball just before the latter is 85 doffed from the winding-spindle Y.

The cutter-operating cam is shown as an approximately-elliptical groove at the rear of the hand-wheel, in which groove is a pin P, projecting from slotted lever Q, which is connected to arm R of angle-lever S, pivoted at T. The cam when turned thus reciprocates the cutter as required.

One of the ball-ending appliances is provided for each winding-spindle and they are all 95 operated simultaneously by the hand-wheel and by the cam H, which operates the cutters.

Instead of securing upon each cutter-bar B a cam-piece F the same purpose can be served by the provision of a rotating cam G', as shown 100 at Fig. 5, having a groove in its periphery similar in shape to the slot in the cam-piece F, this groove acting on a pin or roller on the end of a single transverse shaft D, carrying all the

eye-pointed needles E employed in the machine.

Having now described the invention, what we claim, and desire to secure by Letters Patent, is—

1. In a machine for balling yarn or thread the combination with a winding-spindle, a rod D, a needle E carried by rod D, and having an eye E', means for reciprocating rod D, cutter B, means for actuating the cutter to sever the yarn or thread, hook G between the cutter and the ball of yarn wound on the spindle, means for passing hook G through needle-eye E' and engaging the yarn, whereby the cut end of the yarn will be pulled through eye E', and will be drawn through the outer convolutions of the ball by the backward movement of the needle.

2. In a machine for balling yarn or thread the combination with the thread-cutting mechanism, of a hook secured to the cutter-bar, a

cam-piece also secured thereon, a transverse sliding bar actuated by said cam-piece, and a needle adjustably secured to the sliding bar and having its eye directed toward the cutter-bar, and adapted to be entered by said hook, substantially as and for the purpose set forth. 25

3. In a machine for balling yarn or the like, the combination of thread-cutting mechanism, hook G movable with the cutting mechanism, cam-piece F with cam-slot therein, a transverse sliding bar actuated by the cam-piece, a needle secured to the sliding bar, said needle having an eye E' in the path of hook G, as specified. 30 35

In witness whereof we have hereunto set our hands in presence of two witnesses.

WALTER McGEE.
DAVID McGEE.
